United States Patent Office

Des. 185,326
Patented May 26, 1959

185,326

BOAT ANCHOR

Edward E. Spitz, Brookline, Mass.

Application May 14, 1957, Serial No. 46,163

Term of patent 14 years

(Cl. D71—1)

Fig. 1.

Fig. 2.

Fig. 3.

Fig. 4.

Figure 1 is a plan top view of a boat anchor, embodying my design;

Figure 2 is a bottom plan view of the boat anchor;

Figure 3 is a side elevational view of the boat anchor and

Figure 4 is a cross-section taken along line 4—4 of Figure 3.

I claim:

The ornamental design for a boat anchor, substantially as shown.
